LAFE SWANK, OF ANDERSON, INDIANA, ASSIGNOR TO DWIGGINS WIRE FENCE COMPANY, OF ANDERSON, INDIANA, A CORPORATION OF INDIANA.

GATE-LATCH.

1,127,825.

Specification of Letters Patent.

Patented Feb. 9, 1915.

Application filed July 9, 1914. Serial No. 849,879.

To all whom it may concern:

Be it known that I, LAFE SWANK, a citizen of the United States, residing at Anderson, in the county of Madison and State of Indiana, have invented a new and useful 5 Gate-Latch, of which the following is a specification.

The object of my invention is to produce a gate latch which may be produced at 10 minimum expense and yet be of such character as to be readily operable to release the gate but also capable of insuring automatic holding of the gate in closed position against manipulations of the gate by stock.

15 The accompanying drawings illustrate my invention.

Figure 1 is a front elevation with the gate tongue shown in vertical section; Fig. 2 a section on line 2, 2 of Fig. 1; and Fig. 3 a 20 perspective view of the complete lock and associated gate post and gate tongue.

In the drawings, 10 indicates the main casing of the structure from the front face of which rise two latch hoods 11, 11 which 25 are preferably cast integral with the plate 10. The openings 12, 12 under these hoods 11, 11 extend through the main body 10, as clearly indicated in Fig. 2 and between the two hoods there lies an outwardly extended 30 portion 13, the under face 15 of which is substantially square with the outer face of the plate and of a width substantially equal to the width of the gate tongue 16, the said surface 15 being provided to overlie the 35 tongue 16 when said tongue is in gate-closed position. Extending through the side walls of the hoods 11, 11 and about midway of their height, are openings 17 which can be conveniently formed by cores and these 40 openings are amply large to receive loosely the pivot pins 18 of the latches 20, these pivot pins lying substantially parallel with the outer face of the base 10 and being substantially horizontal and therefore at right 45 angles to the axis of the gate so that the main bodies of the latches 20 swing in planes parallel with the closed plane of the gate. Each latch 20 at its outer or free end is provided with an outwardly and upwardly extended tongue 21, the lower face 22 of which forms a cam for engagement by the gate tongue 16 so as to be automatically lifted by said gate tongue when moving toward the closed position only. Rising from the main 50 body 10 below extension 13 is a guard flange 55

23, the upper surface of which is crowned or downwardly and outwardly extended in opposite directions from the vertical middle.

It will be noticed that, because the latches 20 swing in planes substantially parallel 60 with the closed position of the gate and because the inner faces of the latches 20 are substantially vertical, there can be no possible raising of the latches by any lateral rattling of the gate tongue 16 when it lies 65 between the two latches.

In the construction of my gate latch, no machine work is required except the drilling of the single hole in each latch 20 for the reception of the pivot pin 18 and even 70 that may be avoided by casting the hole although I do not recommend such a procedure because some means would then have to be provided to insure the permanence of the pin 18 in the latch. 75

I claim as my invention:

1. A gate latch comprising a main body having a pair of substantially parallel hooded latch openings and a pair of laterally separated latches pivotally mounted in said 80 latch openings so as to swing in planes substantially parallel with the closed-plane of an associated gate, each of said latches having an outwardly and upwardly inclined finger at its free end, said main body also 85 comprising an outwardly extended portion between the latches to overlie a gate tongue and a crowned flange to underlie said gate tongue.

2. A gate latch comprising a main body, 90 a pair of laterally separated latches pivotally mounted thereon so as to swing in planes substantially parallel with the closed-plane of an associated gate, each of said latches having an outwardly and upwardly 95 inclined finger at its free end, said main body also comprising an outwardly extended portion between the latches to overlie a gate tongue. 100

3. A gate latch comprising a main body having a pair of substantially parallel hooded latch openings and a pair of laterally separated latches pivotally mounted in said latch openings so as to swing in planes substantially parallel with the closed-plane of 105 an associated gate, said main body also comprising an outwardly extended portion between the latches to overlie a gate tongue and a crowned flange to underlie said gate tongue. 110

4. A gate latch comprising a main body having a pair of substantially parallel hooded latch openings and a pair of laterally separated latches pivotally mounted in said latch openings so as to swing in planes substantially parallel with the closed-plane of an associated gate.

5. A gate latch comprising a main body, a pair of laterally separated latches pivotally mounted thereon so as to swing in planes substantially parallel with the closed plane of an associated gate, each of said latches having an outwardly and upwardly

inclined finger at its free end, said main body also comprising an outwardly extended portion between the latches to overlie a gate tongue, and a crowned flange to underlie said gate tongue. 15

In witness whereof, I have hereunto set my hand at Anderson, Indiana, this sixth, 20 day of July, A. D. one thousand nine hundred and fourteen.

LAFE SWANK.
